(57) **CLAIM**

The ornamental design for spoke segment of a vehicle wheel, as shown and described.

DESCRIPTION

FIG. 1 is a perspective view of a spoke segment of a vehicle wheel according to my new design; and,

FIG. 2 is an enlarged front elevational view thereof.

The broken line showing of the rear of the wheel, the round elements on the lip of the rim and the elements on the spoke segment is included for the purpose of illustrating environment and forms no part of the claimed design. The dash dot line on either side of the spoke segment is for the purpose of illustrating the boundary of the claimed design and forms no part thereof.
